RAIL AND WHEEL LUBRICATING
MECHANISM

Raymond A. Birmingham, Buena Vista, Va., assignor of one-third to Theodore E. Shackford, and one-third to Hugh H. Chittum, both of Lexington, Va.

Application May 29, 1939, Serial No. 276,474

4 Claims. (Cl. 184—3)

This invention relates to a rail and wheel lubricating mechanism, and it is primarily an object of the invention to provide a mechanism of this kind which is operated by the wheels of a passing train and in a manner whereby the lubricant is properly delivered to both of the rails of the trackway.

The invention also has for an object to provide a mechanism of this kind comprising a container or casing for an initial supply of lubricant and wherein such container or casing is in operative communication with a greasing member disposed along either or both of the rails of a trackway, together with means operated by the wheels of a passing train for forcing the lubricant within the container or casing out through the greasing member or members.

The invention consists in the details of construction and in the combination and arrangement of the several parts of my improved rail and wheel lubricating mechanism whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view partly in section and partly in elevation illustrating a lubricating mechanism constructed in accordance with an embodiment of my invention and in applied position;

Figure 2 is an enlarged detailed view partly in section and partly in elevation illustrating certain details of construction as herein employed;

Figure 3 is a detailed sectional view taken substantially on the line 3—3 of Figure 2;

Figure 4 is an enlarged fragmentary sectional view taken substantially on the line 4—4 of Figure 1;

Figure 5 is a detailed sectional view taken substantially on the line 5—5 of Figure 4.

Figure 6 shows a form of hand crank that can be used for retracting the pressure head.

As disclosed in the accompanying drawings, R denotes the usual rails of a trackway for rolling stock and disposed along the inner sides of the rails R closely adjacent to the webs thereof but underlying the heads 2 are the greasing members M. Each of these members M, as herein disclosed, is maintained in applied position by the brackets 3 carried by the opposite end portions of

the member M and which brackets are bolted, as at 4, or otherwise effectively anchored to the ties T upon which the rails R are mounted. Each of the members M constitutes an elongated container of predetermined capacity and entirely closed except for the series of discharge openings 5 disposed through the outer side walls 6 of the member M and spaced in a direction lengthwise thereof.

The bottom wall 7 of each of the members M, 10 as herein disclosed, is disposed transversely on an upward and outward incline and in communication with the member M through the bottom wall 7 thereof at substantially its longitudinal center is a downwardly and outwardly inclined 15 induction sleeve 8. Suitably coupled to this sleeve 8 and in communication therewith is an end portion of a conduit 9 preferably a flexible hose. This conduit or hose 9 is of predetermined length and has its opposite or outer end portion coupled 20 to and in communication with an end portion of one of the lateral arms 10 of a T-coupling C. The intermediate or shank arm 11 of the coupling C is connected to the outer end portion of an arcuate discharge pipe 12 coupled, as at 14, to the 25 apex portion of a conoidal cap 15. This cap 15, as herein disclosed, slips upon the lower or bottom end portion of an elongated container or casing 16 and is securely held thereto by the screws 17 or otherwise as may be preferred. The 30 casing or container 16 is of desired dimensions and capacity and held within the lower end portion thereof immediately adjacent to the applied cap 15 is a spider 18. In the present embodiment of the invention the spider 18 is maintained in applied position by the screws 17 hereinbefore referred to although it is believed to be obvious that other means may be used.

Extending axially of the casing or container 16 is a threaded shank 19, the lower or inserted end 40 portion of which is continued by a stem 20 of a diameter less than the diameter of the shank 19. The outer portion of this stem 20 is rotatably received within the central hub or bearing 21 of the spider 18. It is to be particularly noted, 45 however, that the inner end of the shank 19 proper is spaced from the spider 18 to entirely receive the piston or driving head 22. This head 22 threads upon the shank 19 but as the periphery of the stem 20 is smooth it will be at once understood that when the head or piston 22 is entirely upon the stem 20 the same will be free of driving connection with the shank 19. The purpose 50 of this is to prevent pressure by the head or pis-

ton 22 upon the spider 18 with, of course, possible resultant injury to the mechanism.

In practice the casing or container 16 is vertically disposed to one side of the trackway, it being required of course that in making an installation suitable excavation must be made in the road bed.

Mounted upon the upper end of the casing or container 16 is a boxing or housing 23 the top of which is open and having associated therewith a cover 24 hinged, as at 25, to a side wall of the boxing. This boxing 23 has its bottom marginal portion defined by the depending flange 26 which snugly engages around the upper end portion of the casing or container 16 and is locked thereto by the screws 27 or otherwise as may be preferred.

As illustrated in the accompanying drawings, the bottom wall 28 of the boxing 23 has direct contact from above with the upper end of the casing or container 16 and said bottom wall 28 at its axial center is provided with an opening 29 through which is snugly and rotatably inserted an elongated stem 30 extending axially from the upper end of the shank 19 and of a diameter less than the diameter of the shank 19. This reduction in diameter results in a shoulder 31 at the top of the shank 19 proper and which is contacted by the bottom wall 28 of the boxing 23.

This upper stem 30 is slidably disposed thru an elongated sleeve 32 and this stem 30 is coupled to the sleeve 32 by a pin 33 extending transversely therethru with the extremities thereof received within the diametrically opposed slots 34 provided in the sleeve 32 and extending lengthwise thereof. By this means the sleeve 32 and the stem 30 are keyed for rotation one with the other but allowing independent endwise movement of the stem 30 lengthwise through the sleeve 32.

The upper portion of the sleeve 32 and the stem 30 are rotatably disposed through the central bearing or hub 34 of the spider 35. This spider 35 intersects the upper portion of the boxing 23 and is held in place by the screws 36 or otherwise as may be preferred. Threading upon the top portion of the sleeve 32 and contacting with the bearing or hub 34 from above is a retaining nut 37. This nut 37 rotates with the sleeve 32 and provides means to limit the downward movement of the sleeve 32 through the bearing or hub 34.

The lower end portion of the sleeve 32 is formed to provide an outstanding surrounding cup-like flange 38.

Interposed between this flange 38 and the bottom wall 28 of the boxing 23 is an expansible member 39, herein disclosed as a coil spring, encircling the stem 30. This spring 39 serves to constantly urge the shank 19 toward the limit of its upward movement which may be determined by contact of the shoulder 31 at the top of the shank 19 with the bottom wall 28 of the boxing 23, or by contact of the beveled gear 40 with the bearing or hub 34 of the spider from below. This beveled gear 40 is mounted upon the sleeve 32 and locked thereto for rotation therewith by a set screw 41 or the like. This beveled gear 40 is in mesh with a beveled gear 42 keyed, as at 43, within the boxing 23 to the inserted end portion of a shaft 44. This shaft 44 is substantially at right angles to the stem 30. This shaft 44 is of desired length and extends laterally from the boxing 23 toward the trackway thru a protecting pipe 45. One end portion of this pipe 45, as herein disclosed, threads within

an outstanding annular flange 46 carried by the boxing 23 and into a similar flange 47 carried by a side wall 48 of a housing H. This housing H is positioned closely adjacent to and below a rail R of the trackway and is held in position by a bracket 49 secured to adjacent ties T or otherwise as may be preferred.

The shaft 44 extends within the housing H thru the side wall 48 and fixed to the end portion of the shaft 44 within the housing H is a ratchet wheel 50. This wheel 50 is adapted to be engaged by a spring pressed pawl carried by a vertically disposed plunger 51 extending upwardly through the top closing plate 52 for the housing H. The lower end portion of the plunger 51 is snugly engaged within a guide pocket 53 within the bottom portion of the housing H whereby the plunger 51 is supported for up and down movement in a vertical direction. The plunger 51 has its upper extremity terminating in close proximity to the base of the adjacent rail R of the trackway and held to said upper end portion of the plunger 51 by the set screw 54 or the like is the lower portion of an arm 55 depending from the central portion of an operating shoe 56. This shoe 56 is in close contact with the inner side face of the head 2 of the rail R and is normally held extended thereabove by an expansible member 57 of desired tension, herein disclosed as a coil spring, surrounding the plunger 51 and interposed between an enlargement or head 56 carried by said plunger and the bottom of an upstanding protecting socket 58 carried by the plate 52. The upper end of this socket 58, as herein disclosed, is closed by a screw cap 60 through which the plunger 51 is freely directed.

In communication with the casing or container 16 at the top thereof and at a point below the pressure head or piston 22 when in its fully raised or retracted position is a filling spout 61. This spout 61 extends upwardly a desired distance and is adapted to be normally closed by a conventional screw cap 62 or the like.

The stem 30 above the sleeve 32 is squared in cross section, as at 63, so that a hand crank 64 or kindred tool may be engaged therewith to retract the pressure head or piston 22. Should the pressure head or piston 22 be upon the lower stem 30, before said head or piston can be retracted it is required that pressure be imposed upon the shank 19 through the upper stem 30 to move the same against the action of the spring 39 sufficient to allow the lower end of the shank 19 to have desired threaded engagement with the head or piston 22.

It is believed to be obvious from the foregoing description in connection with the accompanying drawings that as a train passes along the trackway the wheels of the rolling stock travelling on one of the rails R will intermittently strike the operating member 56 and depress the same with a resultant intermittent rotation of the shaft 44, gears 42 and 40 and of course the shank 19. The direction of rotation of these parts is such as to cause the head or piston 22 to intermittently travel downwardly and thereby forcing the lubricant, which is preferably oil, within the casing or container 16 to the greasing members M and out through the openings 5 upon the flanges of the wheels travelling along the members M whereby said flanges are effectively lubricated and with consequent effective lubrication of the heads of the rails.

It is, of course, required that the pressure head or piston 22 be held against rotation and in the

present embodiment of my invention wherein the casing or container 16 is circular in cross section, the head or piston 22 in its peripheral portion is provided with a groove or keyway 66 coacting with a key 66 extending along the inner face of the casing or container 16.

From the foregoing description it is thought to be obvious that a rail and wheel lubricating mechanism constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A rail and wheel lubricator comprising a greasing member, means for securing said member along one side of a rail, a supply casing in communication with the greasing member, a threaded shank within the casing, means for supporting said shank for rotary movement and for limited endwise movement, means for normally maintaining the shank at the limit of its movement in one direction, a pressure head within the casing and threaded upon the shank, said shank having a portion upon which the pressure head freely engages with said head is at the limit of its pressure movement, means intermittently operated by the wheels of a passing train for rotating the threaded shank to cause the head to impose pressure upon the lubricant supply within the casing, retrograde rotation of the shank retracting the head, endwise movement of the shank in one direction bringing the shank into threaded engagement with the head when said head is free on the shank.

2. A rail and wheel lubricator comprising a greasing member to be positioned against one side of a rail, a supply casing, a delivery line leading from the supply casing to the member, a pressure head within the casing, a rotatable shank extending within the casing and upon which the pressure head threads, said shank being disposed from the discharge of the casing, the portion of the shank adjacent to the discharge of the casing being unthreaded and upon which the head is received when at the limit of its movement toward the discharge, a sleeve operatively engaged with the opposite end portion of the shank for rotation therewith but permitting the shank and sleeve to have relative lengthwise

movement, means for normally maintaining the shank at the limit of its movement away from the discharge, and train operated means for intermittently rotating the sleeve and shank to cause the head to move toward the discharge.

5

3. A rail and wheel lubricator comprising a greasing member, means for securing said member along one side of a rail, a supply casing in communication with the greasing member, a threaded shank within the casing, means for supporting said shank for rotary movement and for limited endwise movement, means for normally maintaining the shank at the limit of its movement in one direction, a pressure head within the casing and threaded upon the shank, said shank having a portion upon which the pressure head freely engages when said head is at the limit of its pressure movement, means intermittently operated by the wheels of a passing train for rotating the threaded shank to cause the head to impose pressure upon the lubricant supply within the casing, retrograde rotation of the shank retracting the head, endwise movement of the shank in one direction bringing the shank into threaded engagement with the head when said head is free on the shank, and a filling spout in communication with the casing at a point in advance of the head when the head is substantially fully retracted.

15

4. A rail and wheel lubricator comprising an elongated casing to be vertically positioned adjacent to a trackway, greasing members, means for securing said members along the inner faces of the rails of the trackway, the lower portion of the casing having a discharge delivering to both of the members, a rotatable shank disposed axially of the casing, a pressure head within the casing and threading upon the shank, a boxing mounted upon the upper end of the casing and closing said end, said shank having a part extending within said boxing, a sleeve surrounding the portion of the shank within the boxing, means for connecting the sleeve and said portion of the shank for unitary rotation but permitting the same to have limited independent lengthwise movement, means for normally maintaining the shank at the limit of its independent endwise movement away from the discharge of the casing, a member, means for supporting the member adjacent to the rail of the trackway to be intermittently depressed by wheels of rolling stock passing thereover, and an operative connection between said member and the portion of the shank within the boxing to intermittently rotate the shank as the member is intermittently depressed.
